UNITED STATES PATENT OFFICE

157,062

DISPLAY COUNTER

Joshua Gordon Lippincott, Scarsdale, N. Y., assignor to Supurdisplay, Incorporated, Milwaukee, Wis., a corporation of Wisconsin

Application April 9, 1948, Serial No. 145,624

Term of patent 14 years

(Cl. D80—11)

To all whom it may concern:

Be it known that I, Joshua Gordon Lippincott, a citizen of the United States of America and residing at 5 Reynol Crossing, Scarsdale, in the county of Westchester and State of New York, have invented a new, original, and ornamental Design for a Display Counter, of which the following is a specification, reference being had to the accompanying drawings, forming a part thereof.

In the drawings:

Fig. 1 is a three-quarter front perspective view of a display counter showing my new design;

Fig. 2 is a front perspective view of my new design, and

Fig. 3 is an end perspective view of my new design.

I claim:

The ornamental design for a display counter, as shown.

JOSHUA GORDON LIPPINCOTT.
